UNITED STATES PATENT OFFICE.

ULRICH KORNSTEIN, OF NEW YORK, N. Y.

DESIGN FOR A CRUTCH.

53,968.

Specification for Design.

Patented Oct. 14, 1919.

Application filed January 31, 1919. Serial No. 274,379. Term of patent 3½ years.

To all whom it may concern:

Be it known that I, ULRICH KORNSTEIN, a citizen of the United States, residing at New York, in the county of New York and State of New York, have invented a new, original, and ornamental Design for Crutches, of which the following is a specification, reference being had to the accompanying drawings, forming part thereof.

The figure is a front elevation of a crutch, showing my new design.

I claim:

The ornamental design for a crutch, as shown.

ULRICH KORNSTEIN.
